(57) CLAIM

The ornamental design for a protective eyeglass sideshields with comfort safety wing, as shown.

DESCRIPTION

FIG. 1 is a front and top left perspective view of a safety sideshield showing my new design in the environment of an embodiment of glasses frames;

FIG. 2 is a frontal view thereof;

FIG. 3 is a view of a right side view of the left sideshield thereof, the left side view of the right sideshield being a mirror image side view of the left sideshield and therefore is not presented;

FIG. 4 is a left side view of a left sideshield thereof, the right side view of the right sideshield being a mirror image left side view of a left sideshield and therefore is not presented;

FIG. 5 is a rear view thereof;

FIG. 6 is a top view thereof; and,

FIG. 7 is a bottom view thereof.

The broken lines shown on the drawings are for illustrative purposes only and form no part of the claimed design.
